DESIGN FOR A COMBINED ADVERTISING DISPLAY STAND AND BRUSHES THERE- FOR

Ernest B. Wright, Montclair, N. J., assignor to Hanlon & Goodman Co., Belleville, N. J., a corporation of New York

Application February 19, 1936, Serial No. 61,235

Term of patent 14 years

To all whom it may concern:

Be it known that I, Ernest B. Wright, a citizen of the United States and a resident of Montclair, in the county of Essex and State of New Jersey,
have invented a new, original, and ornamental Design for a Combined Advertising Display Stand and Brushes Therefor, of which the following is a specification, reference being had to the accompanying drawing, forming part thereof.

Figure 1 is a top plan view of a combined advertising display stand and brushes therefor showing my new design.

Figure 2 is a front elevational view thereof.

I claim:

The ornamental design for a combined advertising display stand and brushes therefor, as shown.

ERNEST B. WRIGHT.
